CLAIM

The ornamental design for a microwave ovenware, as shown
and described.

DESCRIPTION

FIG. 1 is a perspective view of a microwave ovenware showing my new design in a first embodiment;

FIG. 2 is a bottom perspective view thereof;

FIG. 3 is another perspective view of the microwave ovenware shown in an alternate configuration with one cover partially open;

FIG. 4 is another perspective view of the microwave ovenware shown in an alternate configuration with one cover partially open, shown in an environment of use;

FIG. 5 is a front view of the microwave ovenware shown in FIG. 1;

FIG. 6 is a rear view thereof;

FIG. 7 is a left side view thereof;

FIG. 8 is a right side view thereof;

FIG. 9 is a top plan view thereof;

FIG. 10 is a bottom view thereof;

FIG. 11 is an exploded perspective view of the microwave ovenware;

FIG. 12 is a left side view of the microwave ovenware shown in an alternate configuration with one cover fully open;

FIG. 13 is a left side view of the microwave ovenware shown in an alternate configuration with one cover partially open;

FIG. 14 is a left side view of the microwave ovenware shown in an alternate configuration with both covers partially open;

FIG. 15 is a perspective view thereof;

FIG. 16 is a perspective view of the microwave ovenware shown in a second embodiment;

FIG. 17 is a bottom perspective view thereof;

FIG. 18 is another perspective view of the microwave ovenware shown in an alternate configuration with one cover partially open;

FIG. 19 is a front view of the microwave ovenware shown in FIG. 16;

FIG. 20 is a rear view thereof;

FIG. 21 is a left side view thereof;

FIG. 22 is a right side view thereof;

FIG. 23 is a top plan view thereof;

FIG. 24 is a bottom view thereof;

(Continued)

FIG. 25 is an exploded perspective view of the microwave ovenware;

FIG. 26 is a left side view of the microwave ovenware shown in an alternate configuration with one cover fully open;

FIG. 27 is a left side view of the microwave ovenware shown in an alternate configuration with one cover partially open; and,

FIG. 28 is a left side view of the microwave ovenware shown in an alternate configuration with both covers partially open.

The broken lines showing the food and plate in FIG. 4 is for the purpose of illustrating environment and form no part of the claimed design. All other broken lines illustrate portions of the microwave ovenware that form no part of the claimed design.
